VALET STAND

Sidney C. Derman, Manhasset, and Harold S. French,
Great Neck, N.Y., assignors to Trendsetter Products
Corp., Glen Cove, N.Y., a corporation of New York

Filed Jan. 28, 1963, Ser. No. 73,353

Term of patent 3½ years

(Cl. D33—8)

FIG. 2.

FIG. 1.

FIG. 3.

FIG. 4.

FIG. 1 is a perspective view of a valet stand embodying our new design;

FIG. 2 is a rear elevational view thereof;

FIG. 3 is a top plan view thereof; and

FIG. 4 is a bottom plan view thereof.

We claim:

The ornamental design for a valet stand, as shown.
